UNITED STATES PATENT OFFICE.

ISAAC STROUSE, OF NEW HAVEN, CONNECTICUT.

DESIGN FOR A CORSET.

SPECIFICATION forming part of Design No. 12,690, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes part of this specification, and represents a side view, showing the hip-section complete.

This invention relates to a design for the ornamentation of that part of a corset commonly called the "hip-section"—that is to say, the part of the corset between the front and back, and which extends from under the arm down over the hip; and the design consists in the representation of cords or ribs in series, as shown in the accompanying illustration and herein-after described.

Transversely across the center is the representation of a series of ribs, *a*, with a like series, *b*, transversely across the top, and a like series,

c, transversely across the bottom, the space between the middle and upper series filled by the representation of ribs running diagonally downward and forward, and the space between the middle series and the lower filled by the representation of ribs running diagonally downward and backward, as shown in the accompanying illustration.

I claim—

The design for the hip-section of a corset, consisting of the transverse series of ribs *a* at the center, *b* at the top, and *c* at the bottom, the spaces between the center and upper series filled by the representation of ribs running diagonally upward and forward, and the space between the center and lower series filled by the representation of ribs running downward and backward, as shown in the accompanying illustration.

ISAAC STROUSE.
